PATTERN CHAIN CONTROL MECHANISM

Frank R. Page, Laconia, N. H., assignor to Scott & Williams, Incorporated, Laconia, N. H., a corporation of Massachusetts

Application January 12, 1939, Serial No. 250,607

19 Claims. (Cl. 66—154)

This invention relates to means for controlling the pattern chains of knitting machines and more particularly circular knitting machines having a plurality of yarn feeds and it is an object of this invention to provide means for advancing the pattern chains of circular knitting machines additional fractional portions of the length of a chain link without interfering with or modifying the usual operation of the pattern chain and main pattern drum whereby the number of courses knit in the formation of a part of a stocking may be changed.

In the drawings in which preferred modifications of this invention are shown—

Figure 1 is a fragmentary view in side elevation showing the application of this invention to a Scott and Williams circular knitting machine, only such parts being shown as is necessary to illustrate the invention.

Figure 2 is a view in front elevation of the structure shown in Figure 1, additional related parts being shown to make clear the application of the invention to the knitting machine with which it is associated;

Figures 3 and 4 are views similar to Figure 1 of a construction adjustable to shift the pattern chain different amounts, Figure 3 showing the construction adjusted to shift the pattern chain to the extent of one-third of a link and Figure 4 to the extent of two-thirds of a link;

Figure 5 is a partial view in front elevation of a further modification; and

Figure 6 is a partial sectional view taken on line 6—6 of Figure 5 and showing in side elevation parts of the structure shown in Figure 5.

In the circular knitting machines of the Scott and Williams type the usual arrangement is to rack the pattern chain forward one-third of one of the chain links every fourth revolution of the needle cylinder so that on a single-feed machine one link of the pattern chain corresponds to twelve courses of knitting. This is a reasonably satisfactory arrangement inasmuch as twelve courses of knitting approximate the difference in length between stocking feet of successive sizes and the change from one size to another can be readily made by adding a link to or taking a link from the pattern chain. On a three-feed machine, however, with three courses being knit each revolution of the needle cylinder racking the pattern chain every fourth revolution makes each racking of the pattern chain correspond to twelve courses and a link to thirty-six courses or approximately three sizes. It is necessary, therefore, to provide means on a three-feed machine

for changing the length of the chain with respect to the revolutions of the needle cylinder by a fraction of a length of the chain link. Thus, if the pattern chain can be advanced an extra one or two racks during the knitting of the foot on a three-feed machine the size of the foot is reduced one or two sizes thereby and, if an extra link has also been added to this portion of the pattern chain the length of the foot is increased only two sizes or one thereby instead of the three sizes normally resulting from the addition of a chain link.

In the drawings, the invention is shown in Figures 1 to 4, inclusive, in connection with mechanism for operating the needle cylinder, pattern chain and pattern drum such as is shown in the patent to Scott, No. 1,152,850, only so much of the mechanism of the patent being shown as is necessary to illustrate the invention. As shown in the Scott patent, there is provided a pinion 38 fixed on a sleeve 46 which is journaled in the machine frame A and driven by the usual drive pulley (not shown). The pinion 38 meshes with a gear 80 journaled on a shaft 55 mounted in the frame A and having a pin 61 fixed therein on which is journaled one end of the pitman or link 70. The other end of the link 70 is journaled on a pin 71 mounted in a quadrant 75 which is journaled on a shaft 76 mounted in the machine frame A. The quadrant 75 is formed with an extended or projecting hub having arms supporting pins on which are mounted the pawls 82 and 87, the pawl 87 being arranged to operate the ratchet wheel 86 and sprocket 84 on shaft 80 for advancing the pattern chain 85 while the pawl 82 is arranged to operate the ratchet wheel 81 to rotate the shaft 80. The operation of the ratchet wheel 81 by the pawl 82 is controlled by lugs on the pattern chain 85 engaging the usual means 83 which cause the pawl 82 to advance the ratchet wheel 81 and shaft 80 at irregular intervals in the usual manner.

The quadrant 75 engages a gear 35 to rotate said gear in opposite directions on a shaft 32 as the quadrant is reciprocated. The shaft 32 is journaled in the machine frame adjacent the gear 35 and has an end journaled in the sleeve 46. The shaft 32 is the usual main drive shaft by which the needle cylinder is operated and has the clutch 33 slidingly keyed thereon and operated by the slide 92 to be engaged with either of the gears 35 and 38 to connect the selected gear to the shaft 32 in the usual manner. The slide 92 has a cam follower 88 engaging in the cam track of a drum 80 fixed on the shaft 32,

the track being arranged to shift the slide 82 on its rod 83 to shift the clutch 33 from one gear to the other as the drum 80 is rotated by the ratchet wheel 81 and pawl 82. The construction so far described is the construction shown in the Scott patent and causes the ratchet wheel 86 to be advanced one tooth for every four revolutions of the needle cylinder and the cam drum 80 to be advanced in accordance with the pattern determined by the lugs on the links of the pattern chain 85. The movement of the drum 80 is irregular, some racking movements being long and some short in the usual manner.

To provide the pattern chain 85 with an extra movement, as during the knitting of the instep and sole of a stocking foot there is provided a lever 40 pivotally mounted on a pin 41 secured in the machine frame and having an arm 40^a aligned with a cam 42 attached to the gear 38. The lever 40 is also provided with a second arm 40^b having a cam 40^c adjustably mounted in the end thereof and positioned to be engaged by a pin 95 fixed in an end of the drum 80. Pivotally attached to the arm 40^a adjacent the upper end thereof is a pawl 45 which is bent, as shown in Figure 2, so as to engage the ratchet wheel 86. A suitable stop 47 limits the outward movement of the lever 40.

In the operation of this device, the pawls 81 and 82 advance the pattern chain 85 and drum 80, respectively, until, during the knitting of the portion of the instep and sole, a movement of the drum 80 carries the pin 95 past the lower end of the cam 40^c, raising the cam 40^c and lever 40 to place the lever arm 40^a in position to be operated by the cam 42 on gear 38 and retracting the pawl 45 to engage the next tooth on the ratchet wheel 86. Rotation of the gear 38, which is synchronous with the rotation of the needle cylinder, causes the cam 42 to operate the lever 40 and, through the pawl 45, advance the ratchet wheel 86 to the extent of one tooth. The gear 38 rotates four times for each revolution of the gear 80 so a relation of the operation of the lever 40 by the cam 42 to the operation of the pawl 81, once established, is always maintained thereafter. To make the operation of the pawl 45 effective the pin 95 is placed to lift the lever 40 and shift the pawl 45 at such a time that the cam 42 operates the lever 40 and pawl 45 while the pawl 81 is being retracted so that the movement of the ratchet wheel 86 and chain 85 by the pawl 45 is an added movement thereof and reduces the number of courses knit during the movement of the chain 85 to pattern the foot of the stocking.

In the modified construction shown in Figures 3 and 4 the quadrant 75 operates the pawls 81 and 82 to advance the ratchet wheels 86 and 81 respectively, and the gear 38 is provided with a cam 42 as in the modification just described. The lever 50 to which the pawl 45 is secured, is, however, pivotally supported on a pin 41^a which is placed differently from the pin 41 giving a longer arm 50^a and a shorter arm 50^b than the corresponding arms of the lever 40 of the previous modification. The arm 50^b carries an adjustably mounted cam 50^c positioned to be engaged by the pin 95 on the drum 80. In this construction the positions of the arms 50^a and 50^b and the ratio of their effective lengths is such that the cam 50^c may be adjusted in the arm 50^b so as to cause the pin 95 to shift the pawl to the extent of either one or two teeth on the ratchet wheel 86 without causing the cam

50^c to be positioned so that the pin 95 will not engage the inclined cam face thereof. Movement of the pawl 45 two teeth of the ratchet wheel 86 brings the arm 50^a closer to the cylindrical face on which the cam 42 is carried than does a movement of one tooth so that the cam 42 causes a correspondingly greater operation of the pawl 45 and ratchet wheel 86. A stop 47 limits the outward movement of the lever 50.

In the modified construction shown in Figures 5 and 6 the pinion 38 is fixed on a sleeve 46 journaled in the machine frame A and is driven by the usual drive pulley (not shown). The pinion 38 drives a gear (not shown) to which is pivotally connected an end of the pitman 70 which reciprocates a quadrant 75 provided with a hub 75^a pivotally mounted on a shaft 77. The quadrant 75 engages with a gear 35 journaled on a shaft 32 which is journaled in the machine frame A adjacent the gear 35 and has an end journaled in the sleeve 46. A clutch 33 slidably keyed on the shaft 32 is operated from the clutch operating drum (not shown) to connect either the pinion 38 or the gear 35 to drive the knitting machine in rotary and reciprocating knitting, respectively, in the usual manner.

Journalized on the shaft 77 is a sprocket 84 for the pattern chain 85 and attached to or formed integral with the sprocket 84 is a gear 51 which meshes with a gear 52 fixed on a shaft 53 journaled in the machine frame A. The shaft 53 projects through the frame A and has mounted on the projecting end thereof an operating handle 54. Also fixed on the shaft 53 or connected directly to the gear 52 is a ratchet plate 55.

Projecting from the quadrant hub 75^a and at an angle to the quadrant arm is an arm 78 formed integral with the hub 75^a and pivotally connected at its outer end to a pawl member 79 by a pin 91 which is secured in the arm 78 by a set screw 93 and is of sufficient length to project beyond a side of the pawl member 79. At its free end the pawl member 79 has an extending lug 94 in which is mounted a pin 96 arranged to engage the ratchet wheel 97 for operating the main pattern drum 120. The pawl member 79 is biased to engage the pin 96 in the ratchet wheel 97 by a spring 98 having its opposite ends connected to the pawl member 79 and the machine frame A.

In order to control the operation of pattern drum 120 from the pattern chain 85 in the usual way there is provided a lever 56 pivotally mounted on a rod 57 and having one arm 56^a provided with an adjustably mounted cam 58 positioned to be engaged by lugs 59 on the pattern chain 85. The other arm 56^b of the lever 56 has its outer end formed as a gear section which meshes with a correspondingly formed gear section on the outer end of an arm 62^a of a lever 62 pivotally mounted on the shaft 77. The other arm 62^b of the lever 62 has a pin 63 fixed therein in position to engage the pawl member 79; the levers 56 and 62 being biased by a spring 64 connected to the arms 56^a and 62^a of these levers to hold the pawl member 79 in a position keeping the pin 96 free from the ratchet wheel 97 and being operated by the engagement of a lug 59 on the pattern chain 85 to withdraw the pin 63 from the pawl member 79 and permit the spring 98 to operate the pawl member 79 to bring the pin 96 to the ratchet wheel 97.

To operate the pattern chain 85 the usual one-third of a chain link for each four revolutions 75 of the needle cylinder there is provided a hub

68 pivotally mounted on a rod 71 carried by the machine frame A. Formed integral with the hub 65 are the arms 66 and 67, the arm 67 being extended so as to be engaged and operated by the pin 91 in the arm 78 and the arm 66 pivotally supporting a pawl member 68, one end of which has a projection 68a. The pawl member 68 is biased to engage the projection, 68a with the ratchet plate 55 by a spring 69 connected to the other end of the pawl member 68 and to the arm 66.

To operate the pattern chain 85 the additional portion of the length of a chain link there is provided a lever 100 pivotally mounted at one end on the machine frame A, as at 101, and having a pawl member 102 pivotally mounted at its other end. The pawl member 102 has a laterally projecting pin 103 positioned to engage the ratchet plate 55 and a spring 104 connected to the pawl member 102 and the arm 66 keeps the pin 103 in contact with the ratchet plate 55. The lever 100 is provided with a cam 105 positioned to engage cams on the main pattern drum 120 and is normally held in engagement with the drum 120 by a spring 106 connected to the lever 100 and the machine frame A.

In the operation of the modification just described the reciprocation of the lever 78 and pin 91 by the operation of the quadrant 75 operates the arms 67 and 66 and the pawl 68, 68a to rotate the ratchet plate 55, gears 52 and 51 and the pattern chain sprocket 84, the parts being proportioned to move the pattern chain one-third of a link every four revolutions of the needle cylinder. Movement of the lever 78 also operates the pawl member 78 but movement of the pawl member 78 is ineffective to shift the main pattern drum 120 except when the arm 56 is raised by the engagement of a lug on the pattern chain with the cam 58 on arm 56a. It will be noted that the pattern chain is shifted by the pawl member 68 when the arm 78 moves in one direction and that the pawl member 78 is operated to shift the main pattern drum by movement of the arm 78 in the opposite direction. Operation of the pattern chain by the pawl 102 will be simultaneous with the operation of the main pattern drum by the pawl 78 due to the engagement of the cam on the pattern drum with the cam 105 so there will be no conflict of the additional movement of the pattern chain by the pawl 102 with the usual movement of the pattern chain by the pawl 68, 68a. The extent of the movement of the pawl 102 may be varied by the use of cams of different heights on the pattern drum and, in this way, the operation of the pattern chain may be adjusted to be either an additional one or two-thirds of the length of a chain link.

On the three-feed machine, as pointed out above, advancing the pattern chain an additional one-third of a link will shorten the stocking portion twelve courses or approximately one size while advancing the pattern chain an additional two-thirds of a link shortens the stocking portion twenty-four courses or two sizes. If it is desired to lengthen the stocking portion an additional link is placed in the pattern chain in that portion thereof which patterns the stocking portion it is desired to lengthen. Adding the extra link would normally lengthen the stocking portion thirty-six courses or three sizes, but by advancing the pattern chain either two-thirds or one-third of a link the increase in the length of the stocking portion can be kept to twelve or twenty-four courses, that is, one or two sizes, as

desired. In each case, it will be noted the effect is to reduce the length of the stocking portion relatively to the length normally knit by the length of the pattern chain used.

5 What is claimed is:

1. In a circular knitting machine, a pattern chain, operating means for said chain providing a uniform step by step operation thereof and means providing a variable additional operation of said chain.

15 2. In a circular knitting machine, a pattern chain, operating means for said chain providing a uniform step by step operation thereof and means providing a variable additional operation of the length of one or more steps of the uniform form operation of said chain.

20 3. In a circular knitting machine, a pattern chain, operating means for said chain providing a uniform step by step operation thereof and means providing an additional operation of said chain of a variable fraction of the length of a link of said chain.

25 4. In a circular knitting machine, a pattern chain, operating means for said chain providing a uniform step by step operation thereof and means for operating said chain to provide a variable additional operation of said chain.

30 5. In a circular knitting machine, a pattern chain, operating means for said chain providing a step by step operation thereof and means providing an additional operation of said chain between successive operations of said chain by said first means.

35 6. In a circular knitting machine, a pattern chain, operating means for said chain providing uniformly timed step by step operation thereof and means providing an additional operation of said chain between successive operations of said chain by said first means.

40 7. In a circular knitting machine, a pattern chain, operating means for said chain providing uniformly timed step by step operation thereof and means providing an additional operation of said chain between successive operations of said chain by said first means and means to vary the extent of the operation of said chain by said second chain operating means.

45 8. In a circular knitting machine, a pattern chain, operating means for said chain providing uniformly timed step by step operation thereof, and means for operating said chain a multiple of the operation by said first means between successive operations of said chain by said first means.

50 9. In a circular knitting machine, a pattern chain, means for advancing said chain in uniformly timed uniform steps, means for operating said chain between successive operations by said first means, said additional operation being one or more times the extent of the operation of said chain by said first means.

55 10. In a hosiery knitting machine for knitting stockings of different lengths, a pattern chain for controlling the length of stocking being knitted, operating means for said chain providing a uniform step by step operation thereof for producing a stocking of maximum length, and means providing a variable additional operation of the length of one or more steps of the uniform operation of said chain for producing a stocking of shorter length.

60 11. In a knitting machine, a pattern chain for controlling the length of a fabric portion being knitted, means for operating said chain for producing a fabric portion of a certain length and

70 75

additional means for operating said chain to cause a predetermined variation in the length of said fabric portion.

12. In a knitting machine, a pattern chain for controlling the length of a fabric portion being knitted, means for operating said chain for producing a fabric portion of a maximum length and additional means for operating said chain for causing said fabric portion to be knit of a shorter length.

13. In a knitting machine, a pattern chain for controlling the length of a fabric portion being knitted, means for operating said chain for producing a fabric portion of a maximum length and means for providing a variable additional operation of said chain for producing a fabric portion of a shorter length.

14. In a knitting machine, a pattern chain for controlling the length of a fabric portion being knitted, means for operating said chain for producing a fabric portion of a certain length and means for operating said chain while said first operating means is inactive to cause said fabric portion to be knit of a shorter length.

15. In a knitting machine, a pattern chain for controlling the length of a fabric portion being knitted, means for operating said chain step by step for producing a fabric portion of a maximum length and means for operating said chain between successive operations by said first means to cause said fabric portion to be knit of a shorter length.

16. In a knitting machine, a pattern chain for controlling the length of a fabric portion being knitted, means for operating said chain in uni-

form step by step operations for producing a fabric portion of a certain length and means for operating said chain between successive operations by said first means to cause said fabric portion to be knit of a shorter length.

17. In a knitting machine, a pattern chain for controlling the length of a fabric portion being knitted, means for operating said chain in uniform step by step operations for producing a fabric portion of a certain length and means providing a variable additional operation of said chain of a length of one or more steps of the uniform operation of said chain to cause said fabric portion to be knit of a shorter length.

18. In a knitting machine, a pattern chain for controlling the length of a fabric portion being knitted, means for operating said chain in uniform step by step operations for producing a fabric portion of a certain length and means providing a variable additional operation of said chain of a length of one or more steps of the uniform operation of said chain between successive operations of said chain by said first means to cause said fabric portion to be knit of a shorter length.

19. In a machine for knitting hosiery, a pattern chain for controlling the length of a hosiery portion being knitted, means for operating said chain for producing a hosiery portion of a maximum length and a second chain operating means for providing an additional operation of said chain for causing said hosiery portion to be knit of a shorter length.

FRANK R. PAGE.
